(57) **CLAIM**

The ornamental design for a tire with tread wear indicator, as shown and described.

DESCRIPTION

FIG. 1 is a side perspective view of a tire with tread wear indicator showing my new design;

FIG. 2 is a front elevational view thereof; and,

FIG. 3 is an enlarged fragmentary front elevational view thereof.

The broken lines defining the tread pattern depict environmental subject matter that forms no part of the claimed design.
